Teletype Corporation, Chicago, Ill., a corpora-
tion of Delaware

Application April 27, 1944, Serial No. 533,023

16 Claims. (Cl. 178—17)

This invention relates to printing telegraph apparatus and more particularly to automatic station identification apparatus used in combination with printing telegraph apparatus.

In many printing telegraph systems and networks there are a plurality of remote stations on a loop circuit which communicate telegraphically with a central station at predetermined times in a predetermined sequence. Inasmuch as there are a number of such remote stations, some of which sometimes do not have messages to communicate to the central station, it is desirable to provide means whereby the incoming message at the central station may be identified as to its origin.

Accordingly, an object of this invention is to provide automatic station identification apparatus which will communicate to a central station the origin of the incoming message.

Another object of this invention is to provide automatic station identification equipment in combination with a telegraph transmitter in such a manner that the identification signals will invariably precede the telegraphic message.

A further object of this invention is to provide means whereby the telegraph transmitting apparatus will be held unoperative as to the transmission of messages for a period of time during which the station identification signals are transmitted and thereafter will be allowed to operate in a normal manner.

In general, the apparatus comprises a tape sensing unit in combination with a commutator type transmitting unit, and station identification apparatus. The station identification apparatus, in combination with the above-mentioned units, comprises a cam drum having the cams coded in such a manner as to insure the transmission of predetermined permutation code signals over the transmitting unit, and means to prevent operation of the tape sensing unit during the period of operation of the identification cam drum, thereafter allowing operation of the tape sensing unit to transmit the message code signals over the transmitting unit.

A more detailed understanding of the invention may be had from the following description with reference to the accompanying schematic drawing.

The tape sensing unit and transmitting unit are described only to an extent necessary to understand the present invention and may be understood more fully by referring to Bulletin No. 141, issued in March, 1942, by the Teletype Corporation, Chicago, Illinois, wherein they are described substantially.

The tape sensing unit which is designated generally by the numeral 11 receives the tape 12 from a tape perforating apparatus 13, many types of which are well known in the art. The tape 12

passes over a guide roller 14, moves downwardly and under a taut-tape roller 16 which will be mentioned later, and forms in a loop and passes over a guide roller 17 which is in a horizontal plane with the previously mentioned guide roller 14. The taut-tape roller 16 is supported in two slotted guides 18 and has an outwardly extending arm 19 which controls an electrical contact pair 21, as will be hereinafter described. The tape 12 then passes over a sprocket wheel 22 which is fastened securely to a shaft 23 and which has teeth thereon to engage in the perforated feed holes in the tape 12 and thus feed the tape through the sensing mechanism. The shaft 23 has a ratchet 24 secured to one end thereof by means of which the tape feed operation is effected, as will be later explained.

Immediately after the tape 12 passes from the sprocket 22 it passes over a set of five contact levers 26 each of which has a tape sensing pin 27 extending upwardly from its forward end. The tape sensing pins 27 are adapted under certain operating conditions to probe upwardly to sense the tape in order to determine whether the particular code signal being sensed is comprised of marking or spacing impulses, in a manner well known in the art. The contact levers 26 are pivoted on a shaft 28, each having leftwardly extending arms 29 and downwardly extending arms 31. Each of the contact levers 26 has an individual spring 32 which is connected to the leftwardly extending arm 29 and tends to rotate the contact levers 26 in a counterclockwise direction about the pivot shaft 28, as viewed in the drawing. Each of the leftwardly extending arms 29 of the contact levers 26 has a slot 33 formed at its extremity.

Positioned approximately below the shaft 28 is a contact lever bail 34 which is immediately to the right of the downwardly extending arms 31 of the contact levers 26 and extends across all of the arms 31. The bail 34, mounted pivotally on a pivot shaft 36, has a downwardly extending lug 37.

Also mounted pivotally on the shaft 28 is a feed lever 38 which has a leftwardly extending arm 39 and a downwardly extending arm 41. A spring 42 is connected to the arm 39 and tends to pivot the feed lever 38 in a counterclockwise direction about shaft 28, as viewed in the drawing. The feed lever 38 has a feed pawl 43 mounted pivotally at its rightward extremity, which has a spring 44 connected to a downwardly extending lug thereon and which tends to pivot the feed pawl 43 in a clockwise direction. The feed pawl 43 is situated adjacent to the ratchet wheel 24 and cooperates therewith during certain operating conditions to cause the tape 12 to be fed forwardly. The bail 34, described previously as extending across the downwardly extending arms

31 of the contact levers 26, also extends across the downwardly extending arm 41 of the feed lever 38.

Situated immediately to the left of the slots 33 at the extremities of the rearwardly extending arms 29 of the contact levers 26 are a series of five contact arms 46, one individual to each contact arm 26, which are mounted pivotally on an electrical conductor shaft 47. The right-hand ends of the contact arms 46 which cooperate with the slots 33 are insulated, whereas the remaining portions of the contact arms are electrical conductors. The opposite ends of the contact arms 46, remote from the insulated portion cooperating with the slots 33, form a movable tongue to cooperate with an upper electrical spring contact 48 or a lower electrical spring contact 49. Thus, depending upon the position of the contact arms 46 an electrical contact will be made with either the upper spring contact 48 or the lower spring contact 49, in a manner to be hereinafter described.

The transmitting unit comprises a commutator 51 formed with five equal size segments 52 thereon, each of which is assigned to one impulse of the well-known Baudot five unit code. Two other segments are provided on the commutator face other than the five segments 52, one of which, 53, is assigned to the stop interval while the other, 54, is assigned to the start interval. Thus, the transmitting apparatus is of the start-stop type, the operation of which is well known. A collector ring 56 is provided which is formed in a complete circle concentric to the ring of segments and which is electrically connected successively therewith by means of a distributor brush 57 which is mounted securely to a distributor shaft 58 to rotate therewith.

A motor 59 is provided having a worm gear 61 on the motor shaft which cooperates with and continuously drives a gear wheel 62 positioned about the distributor shaft 58. The distributor shaft is, in turn, driven through a friction clutch 63 cooperating with the gear 62, in a well-known manner. A switch 64 is provided which completes an electrical circuit from an alternating current source to drive the motor 59; obviously, a direct current source may also be used.

Positioned securely to the distributor shaft 58 is a cam 66 which has a stop lug 67 extending therefrom. The stop lug 67 engages, during certain periods of operation, with the end of a stop arm 68 which is pivotally mounted on a shaft 69 and which is normally biased in a counterclockwise direction into engagement with the stop lug 67 by means of a spring 71. The opposite end of the stop arm 68 forms an armature for a magnet 72.

An operating cam 73 is also secured to the distributor shaft 58 and cooperates with a cam follower roller 74 which forms one end of a transmitter operating lever 76 pivotally mounted on a stud 77. The opposite end of the transmitter operating lever 76 has an upwardly extending portion 78 which has an adjusting screw 79 passing therethrough. The adjusting screw 79 is immediately adjacent to the downwardly extending arm 37 of the contact lever bail 34 which was previously mentioned, and cooperates therewith in a manner later to be explained. The adjusting screw 79 has been provided so that an adjustment can be made between the downwardly extending arm 37 of the bail 34 and the upwardly extending portion 78 of the operating lever 76.

The various parts which have been described above are all well-known equipment and are sub-

stantially described in the above-mentioned bulletin issued by the Teletype Corporation. However, it is necessary to describe them herein inasmuch as they form part of the present invention, as will now be set forth.

Adjacent the up-turned end 78 of the transmitter operating lever 76 is a blocking lever designated generally as 81 which is pivotally mounted on a stud 82 and normally biased in a clockwise direction, as viewed in the drawing, by means of a spring 83, which results in its blocking arm 84 being moved out of the locus of operation of the upturned end 78 of the transmitter operating lever 76. The amount of clockwise movement of the blocking lever 81 is limited by means of a stop 86. The arm 87 of the blocking lever 81 is formed with a notch 88 at its extremity and acts as an armature for a magnet 89. Located adjacent the arm 87 and under the control thereof is a contact pair 91. A latching lever 92 having a hook 93 at its one extremity which is provided to engage the notch 88 in the arm 87 of the blocking lever 81 under certain conditions is pivotally mounted on a stud 94 and biased in a clockwise direction, as viewed in the drawing, by means of a spring 96. The lever 92 acts as an armature for a magnet 97.

Also secured to the distributor shaft 58 is a cam 101 which controls a follower roller 102 secured to a lever 103 pivoted on a stud 104. The lever 103 which has a notch 106 at its opposite end, is normally biased in a counterclockwise direction by means of a spring 107. A pawl 108 is pivotally mounted to shaft 103 at 109 and is normally urged in a counterclockwise direction by means of a spring 111. Adjacent the notched end 106 of the lever 103 is a lever 112 which has a locking lug 113 thereon to cooperate with the notch 106 and which is pivotally mounted on a pivot shaft 114 and normally urged in a counterclockwise direction by means of a spring 116. The lever 112 forms the armature for a magnet 117.

Adjacent the pawl 108 is a ratchet wheel 118 which is mounted toward the end of a shaft 119. The shaft 119 is journaled rotatably in bearings, which are not shown, and has a cam sleeve 121 securely fastened thereto. The cam sleeve 121 is formed with a series of five cams 122 thereon which correspond with the five impulses of a standard five unit permutation code and a sixth cam 123 which acts for a special purpose as will be later described. Each of the cams 122 controls an individual adjacent electrical contact pair 124 which is normally in an open condition while the sixth or special cam 123 controls an electrical contact arm 126 which operates two electrical contact pairs 127 and 128.

The cams 122 are formed with depressions in their periphery in a predetermined order so as to close the contact pairs 124 in a manner such as to transmit predetermined station identification permutation code signals. In this manner it is possible to send identification signals such as for instance, the letters CHI designating Chicago, or signals which may be necessary to condition the central station printer for receiving these identification signals, such, for instance, as carriage return, letters shift, figures shift, etc. Depending upon the number of depressions in the cam periphery and the number of teeth on the ratchet 118, it is possible to send out as many station identification signals as desired. A typical station identification signal might comprise

carriage return, letters shift, a three letter identification such as CHI, and a space signal.

The operation of the station identification apparatus and its automatic cooperation with the tape sensing and transmitting apparatus, and the electrical circuits thereof, will now be described.

Upon a manual closing of the switch 129 a circuit is completed from the current source to cause the operation of the motor 59 which results in rotation of the worm gear 61 on the motor shaft and a consequent rotation of the gear 62 about the distributor shaft 58. However, at this time the distributor shaft 58 will not rotate, inasmuch as the stop arm 68 is engaging the stop lug 67 and preventing rotation thereof. Such nonrotation of the distributor shaft 58 is possible because of the friction clutch 63. The distributor brush 57 is at this point on the stop segment 53 of the commutator 51 which is customary in start-stop telegraphy. Upon the manual closure of switch 129, assuming that there is sufficient tape 12 in the loop to allow the taut-tape roller 16 to be in a downward position with its arm 19 closing the contact pair 21, potential will be supplied from grounded battery 131 through the switch 129, through the contact pair 21 which is closed, over conductor 132 and through the winding of relay 133 to ground. Inasmuch as relay 133 is of the slow to operate type, its armature 134 will not be attracted immediately but instead an electrical circuit will also be established from grounded battery 131 through switch 129, through contact pair 21, over conductor 132, through armature 134, over conductor 136, and through the winding of magnet 89 to ground.

The energization of magnet 89 immediately causes its armature, which comprises arm 87 of blocking lever 81, to be attracted resulting in a counterclockwise movement of the blocking lever 81 to a position whereat its blocking arm 84 will be positioned immediately in front of the upturned end 78 of the transmitter operating lever 76. The blocking lever 81 will be held in this position, inasmuch as the lever 92 will move in a clockwise direction under the urging of its spring 96 whereat its hooked end 93 will engage the notch 88 in the end of the arm 87 of the blocking lever 81. This is possible, inasmuch as magnet 97 is de-energized at this time and is not therefore attracting its armature which is lever 92.

As the slow to operate relay 133 has not yet become energized to attract its armature 134, no circuit has been established for initiating rotation of the distributor shaft 58. Thus, the brush arm 57 is positioned on the stop segment 53 and the apex of cam 73 is presented to the follower roller 74. In this position the transmitter operating lever 76 is held in its extreme counterclockwise position with its set screw 19 engaging the contact bail 34 and pivoting it about the shaft 36 to cause its upper portion to engage the downwardly extending arms 31 of the contact levers 26 and the arm 41 of the feed lever 38, pivoting them in a clockwise direction about the shaft 28. The result of this is to hold the sensing pins 27 out of tape sensing position and to prevent the tape feed operation which is dependent on the pawl 43 moving upwardly with respect to the ratchet 24, engaging a tooth, and thereafter moving downwardly to step the ratchet at predetermined times. As the transmission of message signals is dependent upon the pins 27 sensing the tape successively upon a new section being presented thereto through intermittent tape feed, no mes-

sage transmission will occur as long as the blocking arm 84 engages the upwardly extended portion 78 of the transmitter operating lever 76, thus preventing the lever from following the nadir of the cam 73 and releasing the contact bail 34; any such release of the bail 34 would allow the contact levers 26 and the feed lever 38, under the action of their springs 32 and 42, respectively, to operate the tape sensing apparatus 11 in a normal manner.

As previously mentioned, the relay 133 is of the slow to operate type and immediately after the energization of magnet 89 and its causing the blocking lever 81 to be moved in a counterclockwise direction, the armature 134 is attracted to the relay 133. This results in potential no longer being supplied to the magnet 89, resulting in its de-energization. However, the blocking lever 81 will not be able to move back to its extreme clockwise position because, as previously mentioned, the lever 92 through its hooked end 93 cooperating with the notch 88 holds the blocking lever 81 in its locking position.

The movement of blocking lever 81 to its counterclockwise position results in the closure of the contact pair 91 which allows an electrical circuit to be established from grounded battery 138, through closed contact pair 91, over conductor 139, over conductor 140, and through the winding of magnet 117 to ground. The magnet 117 will immediately become energized, resulting in its armature lever 112 being attracted thus allowing the blocking lug 113 to move from the notch 106 of the cam follower lever 103. The magnet 117 remains energized during the transmission of the station identification signals.

As a result of the slow acting relay 133 attracting its armature 134, an electrical circuit is established from the grounded battery 131, through the switch 129, closed contact pair 21, conductor 132, armature 134, conductor 137, the winding of magnet 72 to ground. The energization of magnet 72 results in its armature stop arm 68 being attracted and removed from blocking position with respect to stop lug 67 of cam 66. The rotation of the distributor shaft 58 does not affect transmitter operating lever 76, through cam 73, as the lever 76 is locked out by the blocking lever 81.

As the distributor shaft 58 rotates, its cam 101 moves from rest position with its apex against the roller 102 which results in the lever 103 moving in a counterclockwise direction following the nadir of the cam 101 and the pawl 108 engaging a tooth of the ratchet 118 and causing rotation of the shaft 119 and the cam sleeve 121 secured thereto for a distance of one tooth. The timing of the stepping of the shaft 119, through the movement of ratchet 118 under the action of the pawl 108, is such that the shaft 119 and the cam sleeve 121 thereon will be stepped to its next position by the time that the distributor brush 57 sweeps over the stop and start segments but before the first of the impulse segments 52 has been traversed. The result of the one step rotation of cam sleeve 121 is to present cam depressions to certain of the spring contacts controlling the contact pairs 124, according to a predetermined coding. Those of the contact springs of contact pairs 124 which are allowed to enter depressions in the cam sleeve 122 cause their corresponding contact pairs 124 to close and establish electrical circuits from a common ground through the closed contact pairs 124, over conductors 141 to contact points 142 associated with

the upper spring contacts 48, over the conductors 143, and to the segments 52 corresponding to the particular code. At the time that the distributor brush 57 traverses the segment 52 to which the electrical circuit has just been traced, the circuit will be further completed through brush 57, collector ring 56, and over line conductor 144 to the central station where battery is supplied. Inasmuch as no further stepping will occur until such time as the brush arm 57 traverses all of the segments 52 and returns to the stop segment 53, the cam sleeve 121 will remain stationary for this period of time. Thus, it is assured that any of the contact pairs 124 which have been closed will remain so through the time that the brush arm 57 sweeps over the corresponding segment 52. As the distributor brush 57 reaches the stop segment 53 the cam 101 will present its apex to cam follower roller 102 which results in the cam follower lever 103 moving in a clockwise direction with its pawl 108 moving to the next tooth in the ratchet 118. At the time that the distributor brush 57 reaches the end of the start segment 54, the apex of the cam 101 will no longer be in engagement with the cam follower 20 roller 102 and the cam follower lever 103 will have been allowed to move in a counterclockwise direction resulting in the pawl 108 pivotally mounted thereon moving the shaft 119 and the cam sleeve 121 a step through its engagement 30 with the ratchet wheel 118. Such a movement results in a second set of depressions in the cams 122 being presented to the spring levers of the contact pairs 124, which results in certain of these contact pairs being closed by the movement of their spring lever within the depression in the cam. Thus, a circuit is established as previously traced to the line conductor 144. This results in a second station identification code signal being transmitted over the line conductor 144.

The operation which has just been described will recur according to the number of station identification signals which it is desired to transmit over the line conductor 144, depending upon 45 the number of teeth in the ratchet wheel 118 and the number of codings in the cams 122.

When the shaft 119 and the cam sleeve 121 have been positioned at a point whereat the final station identification signal will be transmitted over the line conductor 144, the special cam 123 is positioned with its depression presented to the spring lever 126. The result of the spring lever 126 entering the depression in the cam 123 is to cause the electrical contact pairs 127 and 50 128 to close. The closure of the electrical contact pair 128 results in grounded battery 146 being supplied over an electrical circuit consisting of contact pair 128 and conductor 147. However, at this time no complete electrical circuit will be established as the follower lever 103 will be following the nadir of the cam 101 which results in the spring arm 148 following the follower lever 103, due to its inherent resilience, thus causing 55 the contact pair 149 to be opened.

An electrical circuit is established through grounded battery 146, contact pair 127, over line conductor 148, and through the winding of magnet 117 to ground. It is to be noted that magnet 117 was energized, as previously mentioned, as a result of the movement of the blocking lever 81 to its blocking position resulting in the closing of the contact pair 91. Therefore, the reason for the closure of the contact pair 127 to sup-

ply battery to the winding of magnet 117 will be apparent upon the next operation to be described.

When the distributor shaft 58 completes the rotation during which the last station identification signal was transmitted, and at the time that the distributor brush 57 reaches the stop segment 53, the apex of the cam 101 will be presented to the cam follower roller 102. The result of this is to cause the follower lever 103 to be moved in a clockwise direction, thereby causing the spring lever 148 to close the contact pair 149. As previously mentioned, an electrical potential has been supplied to the point of the open contact pair 149 from grounded battery 146, contact pair 128, and conductor 147. The circuit is now established from this point through the contact pair 149, over conductor 151, and through the winding of magnet 97 to ground. The energization of magnet 97 causes the locking lever 92 to be attracted which results in its hooked end 93 being removed from engagement with the notch 88 in the arm 87 of the locking lever 81. Inasmuch as the magnet 89 is no longer energized and has not been since immediately after the very start of operation of the apparatus when the slow to operate relay 133 attracted armature 134, the blocking lever 81 is now free to move under the urging of its spring 83 to its normal clockwise limit against the stop 86. This results in its blocking arm 84 moving from blocking engagement with the upturned portion 78 of the transmitter operating lever 76, which leaves the operating lever 76 to operate in a normal manner with respect to the cam 73 and the bail 34.

A second result of the movement of blocking lever 81 is to cause the contact pair 91 to be opened, thus breaking the electrical circuit over conductor 139 that had previously energized the magnet 117. However, as already mentioned, a

second electrical circuit for the energization of the magnet 117 had been traced through grounded battery 146, closed contact pair 127, and the winding of the magnet to ground. As a result, magnet 117 remains energized, thus still attracting its armature 112 thereto. The necessity for causing the magnet 117 to be energized is to allow the cam sleeve 121 to be again stepped thereby positioning it in readiness for another transmission of station identification signals. As a result

50 of the continued energization of magnet 117, the continued movement of distributor shaft 58 results in the cam 101 causing the cam follower lever 103 to once again move in a clockwise direction, thereby resulting in the pawl 108 moving up another tooth on the ratchet 118. As the distributor brush 57 moves to its start segment the apex of cam 101 will no longer be presented to the cam follower roller 102 and the cam follower lever 103 will again move in a counterclockwise direction. This results in the shaft 119 and the cam sleeve 121 being stepped another step to a point whereat all of the contact pairs 124 and the contact lever 126 will be engaged with the periphery of the cams 122 and 123 and will 55 not enter any depressions in the cams. The failure of any of the contact pairs 124 to close results in no electrical circuit being established through the contact points 142 and eventually over the line conductor 144. However, at this point, inasmuch as the blocking lever 81 is no longer in blocked position with respect to the transmitter operating lever 76 the tape sensing pins 27 will be presented to the first line of perforated tape resulting in the selected contact levers 26 moving to a counterclockwise position if any of the

60 65 70 75 80 85 90 95 100

pins sense holes thereabove, thereby resulting in their notched ends 33 causing the arms 46 to be pivoted in a clockwise direction against the upper spring contact 48. The result of such a movement of any of the spring contacts 48 is to establish an electrical circuit from ground, over electrical conductor shaft 47, through electrical conductor arms 46, through the upper contacts 48, through the contact points 142, and over the conductors 143 to the intelligence or code impulse segments 52 of the commutator 51. Thereafter, as the brush 57 connects the respective segments successively with the collector ring 56, marking impulses will be transmitted corresponding to the selected pins over the line conductor 144 as there is battery at the remote station completing the electrical circuit. Those pins 27 which did not enter perforations cause the contact levers 26 to be so positioned that the arms 46 engage the lower spring contacts 49. As these are not connected electrically they correspond to spacing impulses.

As a result of the final step of the cam sleeve 121, the cam 123 will be moved to a position whereat its single depression will not be presented to the contact lever 126, thus resulting in the contact pairs 127 and 128 being opened, as previously mentioned. The result of the opening of the contact pair 127 is to remove grounded battery 146 from the electrical circuit which caused the energization of the magnet 117. Upon the de-energization of the magnet 117, the armature 112 will no longer be attracted and will be allowed to move to its normal counterclockwise position under the urging of its spring 116 whereat its tooth 113 will engage the notch 106 in the cam follower lever 103 and prevent its operation. This results in no further stepping of the cam sleeve 121. Likewise, battery will be removed from the electrical circuit which caused the energization of magnet 97. However, it is no longer necessary to hold the magnet 97 energized, inasmuch as the blocking lever 81 has already moved to its clockwise position, free from its blocking position with respect to the operating lever 76, and thus the lever 92 which forms the armature of magnet 97 can no longer hold the locking lever 81 in its blocking position.

Thus, the complete station identification signal has been automatically transmitted over the line conductor 144 upon the closure of the switch 129 which causes the apparatus to come into operation. At the expiration of the transmission of the station identification signals, the station identification apparatus is automatically disabled and the sensing apparatus is now free to operate to transmit message signals from the tape sensing apparatus 11, through the conductors 143, over the commutator segments 52 and over the line conductor 144.

It is to be noted that in the event that the taut-tape roll 16 should be moved upwardly due to a lack of prepared tape, etc., the arm 19 will no longer exert pressure on the contact pair 21 and it will open. This will result in the stopping of message transmission by the opening of an electrical circuit, in a manner well known in the art. Upon an adequate supply of perforated tape, or the trouble present being overcome, the roll 16 will move downward and the contact pair 21 will be again closed. This will result in an electrical circuit being established which will cause the station identification equipment to operate, as described above, even though transmission may have been halted in the middle of a

message. After the station identification signals are transmitted, normal message transmission will be resumed.

Although a specific embodiment of the invention has been shown and described it will be understood that this embodiment is only illustrative and that various modifications may be made therein without departing from the scope and spirit of this invention.

What is claimed is:

1. In combination, a tape sensing device including means to sense the tape and means to feed the tape, a bail controlling said tape sensing and said tape feeding means, means to operate said bail, means to block the operation of said bail operating means, said blocking means including a blocking lever under the control of a magnet, whereby said bail will not be operated to cause the operation of said tape sensing device, and means to latch said blocking lever in its blocking position.
2. In combination, a tape sensing device including means to sense the tape and means to feed the tape, a bail controlling said tape sensing and said tape feeding means, means to operate said bail, means to block the operation of said bail operating means, said blocking means including a blocking lever under the control of a magnet, whereby said bail will not be operated to cause the operation of said tape sensing device, and means to latch said blocking lever in its operated position, said latching means including a latching lever under the control of a magnet.
3. In a tape transmitter, means to sense a tape, means to transmit permutation code signals according to the setting of said tape sensing means, means to automatically block said tape sensing means upon the initiation of transmission, and means to invariably transmit predetermined station identification code signals during the interval that said tape sensing means are blocked.
4. In a tape transmitter, means to sense a tape, means to transmit permutation code signals according to the setting of said tape sensing means, means to automatically block said tape sensing means upon the initiation of transmission, means to invariably transmit predetermined station identification code signals during the interval that said tape sensing means are blocked, and means under the control of said station identification transmitting means to remove said blocking means after said predetermined station identification signals have been transmitted whereby code signals under the control of said tape may be transmitted.
5. In a tape transmitter, means to sense a tape, means to transmit permutation code signals according to the setting of said tape sensing means, means to automatically block said tape sensing means upon the initiation of transmission, means to invariably transmit predetermined station identification code signals during the interval that said tape sensing means are blocked, and means under the control of said station identification transmitting means to remove said blocking means and to disable said station identification signal transmitting means after said predetermined station identification signals have been transmitted whereby code signals under the control of said tape may be transmitted.
6. In a tape transmitter, means to sense a tape, means to transmit code signals according to the setting of said tape sensing means including a segmented commutator, a distributor shaft, a

brush arm secured to said distributor shaft for rotation therewith and cooperating with said segmented commutator to transmit code signals over a line conductor, means to automatically block said tape sensing means upon the initiation of transmission, a cam distributor drum coded according to predetermined station identification signals, means to rotate said cam distributor drum in a step by step manner under the control of a cam on said distributor shaft, and means to transmit said station identification signals to said line conductor including said segmented commutator and said brush arm.

7. In a tape transmitter, means to sense a tape, means to transmit permutation code signals according to the setting of said tape sensing means including a segmented commutator, a distributor shaft, a brush arm secured to said distributor shaft for rotation therewith and cooperating with said segmented commutator to transmit code signals over a line conductor, means to automatically block said tape sensing means upon the initiation of transmission, a cam distributor drum coded according to predetermined station identification signals, means to rotate said cam distributor drum in a step by step manner under the control of a cam on said distributor shaft, means to transmit said station identification signals to said line conductor including said segmented commutator and said brush arm, and means under the control of said station identification transmitting means to remove said blocking means and to disable said cam distributor drum rotating means after said predetermined station identification signals have been transmitted whereby permutation code signals under the control of said tape may be transmitted.

8. In a tape transmitter, a segmented commutator, a brush arm, tape sensing means, means to transmit code signals under the control of said tape through said segmented commutator and brush arm over a line conductor, means to block said tape sensing means, a cam distributor drum coded according to predetermined station identification signals, and means to transmit said station identification signals under the control of said cam distributor drum through said segmented commutator and said brush arm over said line conductor during the interval that said tape sensing means are blocked.

9. In a tape transmitter, a segmented commutator, a brush arm, tape sensing means, means to transmit permutation code signals under the control of said tape through said segmented commutator and said brush arm over a line conductor, means to block said tape sensing means, a cam distributor drum coded according to predetermined station identification signals, means to transmit said station identification signals under the control of said cam distributor drum through said segmented commutator and said brush arm over said line conductor during the interval that said tape sensing means are blocked, and means under the control of said station identification transmitting means to remove said blocking means after said predetermined station identification signals have been transmitted.

10. In a tape transmitter, means to sense a tape, means to transmit permutation code signals according to the setting of said tape sensing means, a lever under the control of a magnet to automatically block said tape sensing means upon the initiation of transmission, and means

to invariably transmit predetermined station identification code signals during the interval that said tape sensing means are blocked.

11. In a tape transmitter, means to sense a tape, means to transmit permutation code signals according to the setting of said tape sensing means, a blocking lever operating to automatically block said tape sensing means upon the initiation of transmission, a locking lever under the control of a magnet to lock said blocking lever in its blocking position when said magnet is de-energized, and means to invariably transmit predetermined station identification permutation code signals during the interval that said tape sensing means are blocked.

12. In a tape transmitter, means to sense a tape, means to transmit code signals according to the setting of said tape sensing means, a blocking lever under the control of a magnet to automatically block said tape sensing means upon the initiation of transmission, a locking lever under the control of a second magnet to lock said blocking lever in its blocking position when said second magnet is de-energized, means to invariably transmit predetermined station identification code signals during the interval that said tape sensing means are blocked, and means under the control of said station identification transmission means to cause the energization of said magnet associated with said locking lever whereby said locking lever is removed from its locking position with respect to said blocking lever and said blocking lever is removed from its blocking position with respect to said tape sensing means.

13. In combination, a first transmitting device, a second transmitting device, a distributor common to said devices and operatively associated therewith, means to initiate transmission under the control of one of said devices, and means to defer transmission from the other of said devices pending completion of transmission from said one of said devices.

14. In combination, a tape controlled transmitting device, a cam controlled transmitting device, a brush type distributor common to said devices and operatively associated thereto, means to initiate transmission under the control of said cam controlled device, and means controlled by said cam controlled device to defer transmission from said tape controlled device pending completion of transmission from said cam controlled device.

15. In combination, a first means adapted to transmit a variable message, a second means adapted to transmit an invariable message, a distributor common to both said means and operatively associated thereto, means to initiate transmission under the control of said second means, and means controlled by said second means to defer transmission from said first means pending completion of transmission from said second means.

16. In combination, a tape controlled transmitting device, a cam controlled transmitting device, a brush type distributor common to said devices and operatively associated thereto, means to initiate transmission under the control of said cam controlled device, and means controlled by said cam controlled device to defer transmission from said tape controlled device pending completion of transmission from said cam controlled device and thereafter to prevent operation of said cam controlled transmitting device during operation of said tape controlled transmitting device.
